UNITED STATES PATENT OFFICE.

CHARLES COOPS, OF MANCHESTER, ENGLAND, ASSIGNOR TO CHARLES MACINTOSH & COMPANY, LIMITED, OF SAME PLACE.

DESIGN FOR AN INDIA-RUBBER TIRE.

SPECIFICATION forming part of Design No. 20,678, dated April 14, 1891.

Application filed December 29, 1890. Serial No. 378,128. Term of patent 3½ years. Patented in England September 8, 1890, No. 156,210.

To all whom it may concern:

Be it known that I, CHARLES COOPS, a subject of the Queen of Great Britain and Ireland, residing at Manchester, in the county of Lancaster, England, have invented and produced a new and original Design for India-Rubber Tires for Wheels, (registered in Great Britain September 8, 1890, No. 156,210,) of which the following is a specification, reference being had to the accompanying drawing, which represents a sectional view illustrating the form or configuration thereof.

The design is applicable, principally, to the india-rubber tires of bicycles and other velocipedes; but it is also applicable, generally, to the tires of all such wheels as are made with a semicircular or other similar concave metal rim fitted with a tire of india-rubber or other compressible material or compound.

My design for a tire is shown in the sec-

tional view in the accompanying drawing and comprises the curved inner part *a*, with a recess *b* formed therein. The outer part of the tire is tapered at the sides *c* toward the surface *d*, which is thus comparatively narrow. At the center of the tire is an opening or space *e*. 25

I claim as my invention—

The herein-described design for a tire, having the curved portion *a*, with a recess *b*, tapering sides *c*, and a central opening *e*, all substantially as shown and described. 30

In testimony whereof I have signed my name to this specification, in the presence of two subscribing witnesses.

CHARLES COOPS.
